DANIEL M. WINANS, OF BINGHAMTON, NEW YORK, ASSIGNOR TO THE BREWER-TITCHENER CORPORATION, OF CORTLAND, NEW YORK, A CORPORATION OF NEW YORK.

CONTROL SHUTTER FOR ENGINE RADIATORS.

Application filed June 1, 1926. Serial No. 112,771.

This invention more particularly relates to improvements in manually-operated dash-controlled shields or shutter fronts as applied to air-cooled radiators for motor vehicles, especially such in which a supplemental shutter supporting frame is adapted for convenient attachment to or removal from the engine radiator without requiring constructive changes in existing cars. One of its objects is to provide a simple, durable and compact apparatus of this character by means of which the temperature of the motor jacket water may be regulated by air flow control through the radiator core openings and thus maintain the engine under better winter operating condition and guard against freezing of the engine cooling medium.

A further important object is to provide for simple and improved means to selectively cut off the air draft through the bottom half of the radiator core passages and to this end, the plural shutters of the present device have been divided to operate in distinct sections or groups, and these are equipped with suitable manipulating bar means provided with a clutch device adapted to regularly actuate said shutter sections in different combinations. With the clutch engaged, all of the shutters may be made to open or close simultaneously but when disengaged, the upper slat section remains operative while the lower group of shutters may be dropped from said bar and left standing in closed position for the purpose of better protecting the lower portion of the radiator against freezing in extremely cold weather. Effective self-locking screw-controlled adjustment means provide for conveniently meeting various changes in atmospheric or road travel conditions, and when all the shutters are kept fully closed, this allows the cooling system to warm up more rapidly upon starting the motor.

To this end and the accomplishment of other new and useful results, the invention further consists in novel constructive features, combination and arrangement of its several parts, all of which will hereinafter be more fully described and claimed.

Reference is had to the accompanying two sheets of drawings which are illustrative of a specific embodiment of my invention as applied to a motor radiator, in which

like characters of reference indicate like parts, and in which drawings:

Fig. 1 is a vertical elevation in partial section showing a general arrangement of my dished shutter frame applied to the front face of an automobile radiator and also my improved manually operated slat actuating devices comprising a screw control carried up and attached to the dash or instrument board of the vehicle for manipulation from the driver's seat.

Fig. 2 represents an elevational rear view of my assembled shutter frame showing the latch device in partial section and the upper group of slats standing in open position while the bottom slat group is disengaged and thrown into its inoperative or closed position.

Fig. 3 is a sectional view as taken along line 3—3 of Fig. 2.

Fig. 4^A is a partial bottom view of the right corner of Fig. 2 showing the position of the latch plate when the bar clutch is disengaged, while Fig. 4^B is a similar view showing said plate thrown into its clutch engaging position when all the shutters move in synchronism.

Fig. 5 shows a bottom view detail of the screw type of dash control for adjusting the actuating linkage of my shutter.

Fig. 6 is a sectional view as taken along line 6—6 of Fig. 2 and indicates in detail certain features of my improved anti-rattler device as applied to the slat trunnions.

Fig. 7 illustrates the shutter slat construction while Fig. 8 is an end view thereof.

Fig. 9 shows in detail one of the inserted slat racks as secured to the respective side pieces of my shutter frame, and Fig. 10 is a sectional view as taken along line 10—10 of Fig. 9.

Fig. 11 is an elevational view of my assembled shutter frame similar to Fig. 2 except that the actuating bar for the lower group of slats is now engaged and made to open these slats in unison with the upper group of slats.

Referring more particularly to said drawings, A₁ denotes a transversely disposed motor vehicle radiator tank or hollow casing which circumscribes a honeycomb or other cellular core A₂, said core being substantially flat and preferably provided with a plurality of rather closely spaced horizontal air flow

openings or cells extending lengthwise of the vehicle and between the front and rear core faces in the conventional manner. It is preferred to work with a shield or shutter frame that is centrally bumped or dished and provides for a flat flared flange held in place by long bolts extending through the core with the marginal flange fitting mounted adjacent to a portion of the front of the core face so as to substantially command the core openings and permit of controlling the flow of cooling air through such core passages as remain unobstructed.

My fenestrated endless or one-piece rectangular frame housing as such is designated in its entirety by the letter B, and comprises two spaced side pieces B₁ and B₂ of cross-sectional Z shaped profile, the respective ends of which pieces are preferably cross connected by integral top and bottom end pieces of similar profile, such as B₃ and B₄. This fenestrated housing structure may further comprise an outwardly disposed brim portion B₅ inscribing the upstanding web pieces 25 of the aforesaid Z shaped members while the other or inwardly disposed leg thereof forms a flat open face B₆ which is spaced from and lies substantially parallel to the plane of said brim to constitute a centrally dished frame portion wherein my shutter slats are pivotally mounted to command the frame fenestration which opening contour is defined by the lip B₆. If desired, the inner edge of said opening may be inturned in a 35 normal relation to said face B₆ to form an endless lip or moulding member B₆' that trims the opening of this hollow frame as indicated in Fig. 3.

Removably fitted against each inner face 40 of the respective side pieces by means of suitable bolts C₁ or the like, is inserted a slat rack C₁ such as shown in Fig. 9, and this is provided with spaced trunnion apertures or bearings such as C₂, C₂', etc. The 45 disposition of said racks is indicated in the frame assembly Fig. 2 and it will be observed that in this illustrative disclosure, there has been provided only two groups of damper slats or shutters, namely an upper slat group 50 or distinct sectional unit preferably comprising the consecutive slats D₁, D₁', D₁'', etc., and a lower slat group or distinct sectional unit comprising the consecutive slats D₂, D₂', etc.; the respective trunnions thereof being rotatably mounted in the apertures C₂, C₂', etc. 55 of said slat racks. Each such shutter group may be provided with independent tie bar linkages so that these sections may be separately manipulated in the manner presently to be described from which it will become 60 evident that the same underlying principle may also be applied to more than two such shutter sections and that the slats thereof need not necessarily be grouped in consecutive order.

When closed, the adjacent edges of the parallelly mounted shutters preferably overlap each other somewhat to form an effective seal for the air flow through the radiator core. The proportions of the slat are preferably such that when closed, the offset swinging edge of one slat may be made to substantially abut the outer surface of the adjoining tubular trunnion portion of the next adjacent slat in the fashion indicated 75 by the lower closed section in Fig. 2; and it will further be observed that the slats are kept relatively narrow to admit of opening them inward toward the adjacent radiator core face but without interference therewith. 80 The complementary demountable slat racks such as C₁ are snugly nested within their respective side pieces B₁ and B₂ and designed to make the inturned bearing flange C₈ of these racks fall behind their adjacent frame 85 lips B₆ as shown in Fig. 6, the length of the slats being preferably kept slightly shorter than the span distance between the inner faces of said lips to allow the consecutive slats to close thereagainst and present a neat 90 trimmed appearance. One of the transverse slat edges is further equipped with an integral actuating arm D₇ which may initially be stamped out integrally therewith and then bent up in a normal relation to the face as 95 shown. Said arm D₇ is provided with a perforated hole or boss D₈ which is freely fulcrumed to its tie bar and operated thereby.

All slats are preferably similarly constructed and the slats of each separate group 100 are connected together into a unit section for the purpose of opening or closing the upper and lower slat sections independently of each other. If desired, both slat sections may also be operated simultaneously from a 105 single actuating cord or cable and to this end, the slats D₁, D₁', etc. making up the upper section, are connected together through the tie bar E₁ which is disposed alongside one end of said slats to impart a common 110 pivotal movement to all such slats about their respective trunnions and cause them to be held in any desired fixed pivotal position. This bar E₁ is shown concealed within the dished portion of my frame B so as to be 115 stow a neat external finish to my shutter front and prevent marring the appearance of the car radiator to which it may be applied. In like manner, the slats D₂, D₂', etc. comprising the lower section are 120 connected together through a separate shorter tie bar E₂ which similarly actuates in unison all the slats D₂, D₂', etc.; said bar is equipped with a lower extension member E₂', the extremity of which may be rounded and 125 made to lie flush with the outer face of the sloping web wall B₄ when the lower slat section is closed, all as is indicated in Fig. 3. It will be further observed that the middle portion of the upper tie bar E₁ is laterally 130

offset at E_1 and terminates in a downward extension E_1' which lies alongside the lower tie bar E_2 and projects beyond the rounded end of said extension E_2' when set in the adjusted position represented by Fig. 2.

In the present disclosure, both bar extension members are adapted to project and freely slide through a suitable slot B_7 cut into the sloping web wall of the end piece B_4 and these members are provided with interconnecting clutch means designed to be engaged or disengaged for cooperative purposes. The outermost extension E_1' may be provided with an aperture or female part E_3 while the inner extension E_2' may be equipped with an overhung clutch pin or male part E_4 adapted to fall into said aperture E_3 when the pin is made to move into alignment therewith. In order to allow of an automatic engagement of these clutch parts, the extension E_1' may be given a small initial bend for the purpose of maintaining a continuous resilient side thrust against the overhung pin E_4 mounted in the adjacent cooperating bar E_2' , and if desired, said extension members may be held in proper alignment by the use of suitable guide sleeves or the like (not shown).

The outer face of the transverse bottom web wall B_4 carries a latch plate E_5 swivelly mounted thereon by means of the fulcrum E_6 ; said latch may be further equipped with a rounded toe or cam element E_5' adapted to bear against the face of the free lower end of said longer bar extension E_1' and this toe serves to thrust said extension outwardly and away from the fulcrum E_6 whenever said latch is forced into the position indicated in Fig. 4^A, an upturned finger piece E_7 being provided to facilitate such manipulation. It will be observed that my entire slat actuating mechanism except the tie-bar extension, is mounted and concealed within the frame housing in a manner suited to properly meet present day sales resistance, also that my clutch devices have been centralized and the control thereof brought outside of the frame proper where it can be conveniently manipulated.

The outermost tie bar E_1 is further provided with a stanchion or overhung pin E_8 adapted to engage a hook end of the helical spring E_9 or other suitable resilient tensioning means, while the other end of this spring may be attached to the fixed post E_{10} , preferably riveted into the inserted slat rack C_1 and made removable therewith. The essential function of the spring E_9 is to resiliently oppose rotation of slats in one direction and bring about the automatic return of the slats into initial position whenever the actuating force is released. Said spring may be initially stretched to bring a substantial tension to bear between said spaced pins E_8 and E_{10} and is preferably disposed to exert an

opening tendency on part of all the shutters making up the uppermost slat section. When the clutch pin E_4 is allowed to fall into engagement with the aperture E_3 to interlock the tie-bars, said single spring member E_9 is also made to exert an opening tension upon the lower slat section. Attached to the upper end of the bar E_1 through the stanchion E_8 or otherwise, is a flexible cable A_3 or other suitable actuating means which may extend upwardly to run over the guide pulley C_4 , the latter being preferably secured to one of the racks by means of the bracket C_5 as shown in Figs. 9 and 10 and made removable therewith. The lateral disposition of the pulley C_4 is preferably made to fall within the width of the core A_2 as indicated so that said cable A_3 may be run through one of the radiator core passages and carried back under the engine hood to the dash or instrument board A_4 in the manner shown in Fig. 1. The cable is then manipulated by means of a screw-type control device which as a unit is preferably placed in juxtaposition to the vehicle seat and in convenient reach of the driver.

As detailed in Fig. 5, my distant shutter control device is designated in its entirety as F and preferably comprises a forked clamp or other suitable body member F_1 which in the present showing is adapted to straddle said board A_4 and to be removably secured thereto by means of a lock screw F_2 or the like, all without requiring a hole to be bored through the board A_4 or otherwise defacing the same when the clamp is removed. Said clamp may further be equipped with depending body lug F_3 and a suitable fulcrum pin F_4 , therefor upon which is mounted a multiplying lever F_5 . One of said lever ends may be provided with a series of spaced holes such as F_6 into one of which the free end of the cable A_3 may be adjustably tied to produce a lever multiplying effect upon the cable relative to the longitudinal movement afforded by said screw. A self-locking adjusting screw F_7 engages said lug and thrusts against another portion of the lever, so that when the screw F_7 is adjustably turned and forced against one end of the control lever F_5 , this will cause the lever to be rocked and thus exert a sufficiently strong take-up pull upon the cable A_3 to lift the top end of the tie bar E_1 with but moderate effort and thus easily open the upper slats against the resistance of the spring E_9 . Such distant control equipped with my self-locking thumb screw regulating device imparts to the cable a delicate vernier-like adjustment and permits of accurately setting and holding the shutters against slat tension into any position without being obliged to resort to a step-wise or other similar coarse regulation.

It is emphasized that by virtue of my dis-

tant screw control device, this wedge agency easily moves the interconnected slats through the cable connection from one into any other setting with perfect continuity and certainty of action. Furthermore, where the tie-bar is used in cooperation with my described screw adjustment means, the multiplying effect given to the lever thereof can obviously be made to reduce to a minimum the screw 10 turns needed for changing the slat setting. Such simultaneous slat and lever operations offer a further advantage in that the thread pitch of the thumb screw may readily be made sufficiently fine to allow of a convenient 15 slat manipulation without obliging the shutter user to pull directly by hand against full tension of the cable return spring. It is preferred to resort to a relatively strong 20 spring action in connection with my screw adjustment because the slats are then better held in position against heavy driving winds and unlikely to be jarred out of adjustment when subjected to uneven road or like disturbances.

25 While the clutch pin E_4 is held out of engagement with its cooperating aperture E_3 by placing the latch plate E_5 in the position shown in Fig. 4^A, the cable A_3 is not allowed to move the lower slat section. Furthermore, in order to better hold these disengaged shutters in fixed position, means are provided to augment the trunnion friction of the various slats, and at the same time to serve as anti-rattler devices in case 30 the trunnion bearings should become enlarged from excessive wear. For such purposes, I preferably provide for a pair of continuous flexible steel strip members such as C_6 extending lengthwise of the respective 35 slat racks such as C_1 and crosswise of the respective ends of each slat mounted therein, as indicated. Each such strip is arranged to span its adjacent trunnion ends and is intended to resiliently bear thereagainst. In 40 order to set up the desired adjustable or followup thrust for all the trunnions, each rack C_1 is further equipped with a series of inturned strip clips C_7 disposed intermediate the respective trunnion bearings such as 45 $C_2, C_2', \dots$, shown in detail by Fig. 9. The tension which the bridging strip is made to 50 exert upon the respective trunnions is regulated by the extent to which the various spaced clips are sprung down against the top of their underlying strip C_6 , and it is pointed out that by this means it becomes 55 possible to independently adjust the degree of friction and also take up wear on part of any individual trunnion in order to maintain any desired trunnion action as a whole. 60 It will be apparent when the lower slat section is drawn into open or closed shutter position, such adjusted trunnion friction allows of retaining such setting against ordinary car vibration.

Additional means are however provided for more securely locking the lower section in its closed position by the use of the latch device E_5 ; for this purpose the extension E_2' of the innermost tie-bar is purposely foreshortened with respect to the extremity 70 of the adjacent extension E_1' , the respective length being such that when the lower slat section comprising slats $D_2, D_2', \dots$, is moved into closed position by turning 75 the thumb screw F_7 , the rounded extremity of said extension E_2' will be fully raised and lie flush with the top of the face of the latch plate E_5 whereupon the latter may be pressed home underneath the tie bar E_2 and 80 thus hold the same in place. This in turn, locks the lower shutter section in closed position, but in order to allow the plate E_5 to be fully turned toward the adjacent brim portion B_5 as shown in Fig. 4^A, its toe E_5' 85 will at the same time wedge the longer bar extension E_1' away from the adjoining bar E_2 as is indicated in Fig. 2. Hence, when the plate E_5 has been allowed to assume this latched position, the clutch pin E_4 will have 90 been withdrawn out of the bar aperture E_3 and thus allow the upper slat section to be regulably opened or closed independently of the locked lower section. This particular latch plate setting is intended to apply when 95 it is desired to protect the lower portion of the radiator against freezing.

In the event that it is desired to pick-up 100 the lower slat section and actuate the same in unison with the upper slat section, the latch plate E_5 must be deliberately turned outwardly and away from the frame brim as shown in Fig. 4^B which releases the resilient tie bar extension E_1' and allows the same to 105 slidably ride upon the overhung clutch pin E_4 carried by the other bar E_2 . When thereupon the upper slat section is also brought 110 into its closed position by further manipulating the adjusting screw F_7 , this will draw the bar E_1 upward until its aperture E_3 falls 115 into alignment with the pin E_4 , whereupon the clutch device becomes engaged and the two interlocked tie bars E_1 and E_2 are caused all the shutters to operate likewise 120 from said dash control.

Should it be desired to again bring about a disengagement of the interlocking clutch device, all the shutters are preferably drawn into their closed position which in turn 125 raises the tie bar extension E_2' into its extreme upper position and allows the latch plate to enter underneath the same, when the toe E_5' again wedges the bar extension E_1' apart from the bar E_2 and withdraws the clutch pin E_4 in the manner previously described. Furthermore, should the cable A_3 unwittingly become ruptured, the described resilient urge on part of the spring E_6 will then throw the slats into open po- 130

sition and prevent possible damage by overheating the car motor.

The present shutter devices are especially designed to facilitate economical manufacture and convenient assembly of the movable parts, and by the use of the described rack members, replacement of any defective slat or repairs to the actuating mechanism may easily be made.

10 It is further pointed out that in the present invention the slot sections are not successively operated as has heretofore been conventional practice, but instead a certain slat section may be selectively disengaged 15 and thrown out of action with respect to the active tie-bar movements but when the clutch means are placed into operative connection, all such shutters are made to move together in exact synchronism or phase relation, and this particular mode of manipulating the respective shutter sections affords a 20 number of outstanding advantages especially as regards extreme simplicity of mechanism and reliability of action for the purpose intended.

Not only is the described slat mechanism concealed within the dished portion of my shutter front but the unitary screw type of dash control is operatively connected there- 30 with by a flexible cable which latter may also be concealed under the engine hood. Such improved cable disposition combined with said screw manipulation of the slats enhances the marketability of my shutter 35 and represents a thoroughly practicable entity of which all elements can readily and neatly be attached to substantially all makes of existing cars at the minimum installation expense and without requiring any alterations to the car structure.

40 It will be understood that various changes in the details and arrangement of my device may be resorted to, such for instance as making the latch plate operable from the dash 45 or the dividing of the plural slats into more than two separate sections and the like, all without departing from the spirit and scope of my invention heretofore described and more particularly pointed out in the appended claims.

50 I claim—

1. In a radiator shutter arranged to adjustably control air flow therethrough, a frame member provided with a plurality of 55 parallelly disposed shutter slats pivotally mounted therein adapted to move between open and closed positions and which slats are divided into a number of distinct groups of several slats each to constitute separate 60 sectional units, an independent tie-bar means mounted within said frame for interconnecting the respective slats comprised in each such group and of which one such bar is provided with an extension member slidably disposed in overlapping co-operative 65

relation to another adjacent bar, spring means urging said slat units into open position, operating means for simultaneously actuating all of said shutter sections in synchronism against spring tension, and clutch 70 means acting between the extension member and said adjacent other bar for disconnecting a sectional unit from the others to render said one unit inoperative.

2. In a radiator shutter arranged to adjustably control air flow therethrough, a frame member provided with a plurality of parallelly disposed shutter slats pivotally mounted therein and adapted to move between open and closed positions, said slats being divided into a number of distinct groups of several slats each to constitute separate sectional units, an independent tie-bar means mounted within said frame for interconnecting the respective slats comprised in each such group and of which one such bar is provided with an extension member slidably disposed in overlapping co-operative relation to another adjacent bar, 80 tension means resiliently opposing slat rotation in one direction of movement, operating means for simultaneously actuating all of said shutter sections in synchronism against spring tension, clutch means acting between the extension member and said adjacent other bar for disconnecting a sectional unit from the others to render the same inoperative, and means latching said inoperative unit in closed shutter position.

3. In a radiator shutter arranged to adjustably control air flow therethrough, a frame member provided with a plurality of parallelly disposed shutter slats pivotally mounted therein and adapted to move between open and closed positions, said slats being divided into a number of distinct groups of several slats each to constitute separate sectional units, an independent tie-bar means for interconnecting the respective slats comprised in each such sectional unit, a clutch device adapted to interlock two of said tie-bars, means for simultaneously disengaging said clutch and locking one of said last named tie-bars in closed slat position.

4. In a radiator shutter arranged to adjustably control air flow therethrough, a frame member provided with a plurality of parallelly disposed shutter slats pivotally mounted therein adapted to move between open and closed positions and which slats are divided into a number of distinct groups of several slats each to constitute separate sectional units, an independent tie-bar means mounted within said frame for interconnecting the respective slats comprised in each such sectional unit and of which one such bar is provided with an extension member slidably disposed in overlapping co-operative relation to another adjacent 115

bar, spring means urging said slat units into open position, operating means for actuating the aforesaid one tie bar, and a clutch device associated with said extension member and adapted to interlock the aforesaid another tie-bar therewith for simultaneously operating both bars in synchronism.

5. In a radiator shutter arranged to adjustably control air flow therethrough, a frame member provided with a plurality of parallelly disposed shutter slats pivotally mounted therein adapted to move between open and closed positions and which slats are divided into a number of distinct groups 10 of several slats each to constitute separate sectional units, an independent tie-bar means concealed within said frame for interconnecting the respective slats comprised in each such sectional unit and of which one 15 such bar is provided with an extension member slidably disposed in overlapping co-operative relation to another adjacent bar, spring means urging said slat units into open position, a clutch device acting between the extension member and the aforesaid adjacent bar for interlocking purposes, and slat actuating means including a cable which during the engagement of said device is adapted to move the aforesaid other bar 20 through the medium of said one bar having the extension member.

6. In a radiator shutter arranged to adjustably control air flow therethrough, a frame member provided with a plurality of parallelly disposed shutter slats pivotally mounted therein to move between open and closed positions and which slats are divided into a number of distinct groups of several slats each to constitute separate sectional 35 units, an independent tie-bar means for interconnecting the respective slats comprised in each such sectional unit and of which one such bar is provided with an extension member slidably disposed in overlapping relation to another adjacent bar, spring means urging said slats into open position, operating means for actuating said sectional units against spring tension, and control means associated with said extension and adapted 40 to co-operate with the aforesaid other bar to allow said one sectional unit to operate while said another unit remains inoperative.

7. In a radiator shutter arranged to adjustably control air flow therethrough, a slotted frame member provided with a plurality of parallelly disposed shutter slats pivotally mounted therein which slats are divided into two groups comprising several slats each to constitute separate upper and lower sectional units, an independent tie-bar for each of said units, the respective tie-bars being provided with extension members adapted to freely project through the frame slot, clutch means serving to interlock said 55 tie-bars, and latch means disposed outside

of said frame and adapted to manipulate said clutch for disengaging purposes.

8. In a radiator shutter arranged to adjustably control air flow therethrough, a frame member provided with a plurality of parallelly disposed shutter slats pivotally mounted therein and adapted to move between open and closed positions, said slats being divided into two groups comprising several slats each to constitute separate upper and lower sectional units, an independent tie-bar concealed within said frame for each of said units and of which one such bar is provided with an extension member disposed in overlapping co-operative relation to the other bar, spring means exerting an opening tension upon the upper slat unit, actuating means adapted to adjust the setting of said upper unit in any desired position against spring tension, clutch means disposed between said extension and the aforesaid other bar adapted to detachably connect said units and serving to impart a synchronized movement to both units in response to a change in setting on part of the upper unit.

9. In a radiator shutter arranged to adjustably control air flow therethrough, a frame member provided with a plurality of parallelly disposed shutter slats pivotally mounted therein and adapted to move between open and closed positions, said slats being divided into two groups comprising several slats each to constitute separate upper and lower sectional units, an independent tie-bar for each of said units, actuating means operatively connected to both of said tie-bars and adapted to adjust the setting of all of the slats in one and the same position, means serving to disengage said units and lock the lower unit in its closed position while the upper unit remains operative.

10. In a radiator shutter arranged to adjustably control air flow therethrough, a frame member provided with a plurality of parallelly disposed shutter slats pivotally mounted therein and adapted to move between open and closed positions, said slats being divided into two groups comprising several slats each to constitute separate upper and lower sectional units, an independent tie-bar concealed within said frame for each of said units and of which one such bar is provided with an extension member disposed in overlapping co-operative relation to the other bar, actuating means including a clutch device operatively connecting the aforesaid overlapping tie-bars together and adapted to adjustably set all of their slats in one and the same position, means for disengaging said clutch to allow the upper unit to actuate independently of the lower unit.

11. In a radiator shutter arranged to adjustably control air flow therethrough, a frame member provided with a plurality of

- parallelly disposed shutter slats pivotally mounted therein and adapted to move between open and closed positions, said slats being divided into two groups comprising
- 5 several slats each to constitute separate upper and lower sectional units, an independent tie-bar for each of said units, actuating means including a clutch device operatively connecting the said tie-bars together, said
- 10 actuating means being adapted to operate through the tie-bar of the upper unit and serving to set all of the slats in closed position prior to disengaging the clutch, and means including a clip member for augmenting slat trunnion friction to retain the lower unit in said closed position while the upper unit remains operative.
12. In a radiator shutter arranged to control air flow therethrough, a frame member
- 20 provided with spaced side-pieces each provided with trunnion apertures serving to mount therebetween a plurality of parallelly disposed shutter slats, the trunnion ends of each such shutter being adapted to project
- 25 through their respective apertures in one of said side-pieces, a resilient strip member extending lengthwise of said one side-piece and arranged to span the protruding slat trunnions thereof, and clip means disposed
- 30 intermediate certain of the last named trunnions and adapted to yieldingly hold said strip against said trunnions.
13. In a radiator shutter arranged to control air flow therethrough, a frame member
- 35 provided with spaced side-pieces each provided with trunnion apertures serving to mount therebetween a plurality of parallelly disposed shutter slats, the trunnion ends of each such shutter being adapted to project
- 40 through their respective apertures in one of said side pieces, a resilient strip member extending lengthwise of said one side-piece and arranged to span the protruding slat trunnions thereof, and a plurality of clip
- 45 means disposed intermediate certain of the last named trunnions and adapted to yieldingly hold said strip in engagement therewith, and adjusting means for changing the degree of tension imposed upon the trunnions by said strip.
14. In an automobile radiator shutter arranged to control air flow therethrough by manual adjustment made from the driver's seat, a frame member provided with a plurality of shutter slats pivotally mounted therein, a reciprocative spring controlled tie-bar disposed alongside one end of said slats and serving to rock the same in unison, cable means attached to said bar and adapted
- 55 to actuate the same against spring tension in one direction of movement, and a lever fulcrumed in juxtaposition to the driver's seat and operatively connected with said cable, and self-locking manually operable
- 60 screw means adapted to impart a vernier-
- like adjustment to the lever for setting of said slats in unison to any extent desired by the operator.
15. In an automobile radiator shutter arranged to control air flow therethrough, a dashboard, a frame member provided with a plurality of shutter slats pivotally mounted therein, a spring controlled tie-bar disposed alongside one end of said slats and serving to rock the same in unison between
- 75 open and closed positions, cable means adapted to actuate said bar against spring tension, a self-locking adjusting screw member carried by a body adapted to be detachably clamped to the dashboard, and a fulcrumed lever member operatively connected with said cable and engaged by the screw, both of the aforesaid members being placed in juxtaposition to the driver's seat and adapted to be manually operated therefrom
- 80 to adjustably set said lever and impart a simultaneous vernier-like setting to all said slats.
16. In a shutter apparatus arranged to adjustably control air flow through an engine radiator core, a frame member comprising a pair of spaced side-pieces of Z shaped cross-sectional profile each being provided with an inturned lip member respectively disposed along the innermost edges thereof,
- 90 an inserted slat rack equipped with spaced trunnion apertures secured alongside each of the respective side-pieces, said lip members being respectively disposed inwardly of and in overhanging relation to their adjoining racks, and a plurality of shutters each having a trunnion projecting beyond the ends thereof respectively adapted to engage an aperture in each of said racks, said slats being arranged to open inwardly toward said core and to close against one of the inturned lip members.
- 100
17. In a radiator shutter front applied to automobile engine purposes and arranged to be manually adjusted from the driver's seat, the combination with a cellular core for the radiator having front and rear faces; a fenestrated dished frame member disposed adjacent to the front face of said core with a plurality of shutter slats pivotally mounted to rock within the dished frame portion and control air flow through the frame fenestration; a reciprocative tie-bar concealed within said dished frame portion and serving to interconnect one end of the respective slats; tension means resiliently opposing slat rotation in one direction of movement; cable means extending through the radiator core and adapted to simultaneously rock said plural slats; a body member having a fulcrum located in juxtaposition to the driver's seat; a lever mounted on said fulcrum and operatively connected to the rear end portion of said cable; and a manipulative self-locking screw means cooperating
- 105
- 115
- 120
- 125
- 130

with said lever to conjointly set the slats against said tension means into any position of adjustment.

18. In a radiator shutter apparatus applied to automobile engine purposes and arranged to be manually adjusted from the driver's seat, the combination of a fenestrated frame provided with a plurality of shutter slats pivotally mounted to rock with-
10 in said frame and control air flow through the fenestration thereof, said slats being divided into groups of several slats each to constitute separate sectional units; separate reciprocative tie-bars mounted within said frame and respectively interconnecting the slats comprised in each such unit; a coupling means acting between said tie-bars adapted to release a sectional unit and ren-

der the latter inoperative with respect to the slats of the remaining units; tension 20 means resiliently opposing rocking movement in one direction and serving to return said remaining slats into initial position; cable means adapted to actuate said remaining slats; a fulcrumed lever operatively 25 connected to said cable; and a cooperating screw means adapted for manipulation from the driver's seat to pull the cable against the resilient opposition of said tension means and simultaneously set said remaining operative slats through self-locking spiral wedge action into any position of adjustment.

In testimony whereof, I have herewith set my hand this 28th day of May, 1926.

DANIEL M. WINANS.
